DESIGN FOR A GALLERY AIR MACHINE GUN

Bert A. Hannigan, Van Nuys, Calif.

Application May 27, 1940, Serial No. 92,633

Term of patent 7 years

all whom it may concern:

Be it known that I, Bert A. Hannigan, a citizen of the United States and residing at Van Nuys, in the county of Los Angeles and State of California, have invented a new, original, and ornamental Design for a Gallery Air Machine Gun, of which the following is a specification, reference being had to the accompanying drawings forming a part thereof.

Fig. 1 is a side elevational view of a gallery air machine gun showing my new design; and
Fig. 2 is a front elevational view of the gun.

I claim:

The ornamental design for a gallery air machine gun, substantially as shown.

BERT A. HANNIGAN.
